United States Patent Office.

BIDDLE ARTHURS, OF PITTSBURG, PENNSYLVANIA.

Letters Patent No. 70,679, dated November 12, 1867.

HOT-AIR FURNACE.

The Schedule referred to in these Letters Patent and making part of the same.

TO ALL WHOM IT MAY CONCERN:

Be it known that I, BIDDLE ARTHURS, of Pittsburg, in the county of Allegheny, and State of Pennsylvania, have invented a new and useful improvement in Hot-Air Furnaces; and I do hereby declare the following to be a full, clear, and exact description thereof, reference being had to the accompanying drawings, making a part of this specification, in which—

Figure 1 is a vertical longitudinal section of my improved heating-furnace; and

Figure 2 is a transverse section, formed by a vertical plane passing through my improved heating-furnace forward of the rear wall of the fire-space.

Like letters of reference indicate like parts.

My invention relates to that class of hot-air furnaces employed to heat or warm dwelling-houses, hotels, public edifices, and buildings generally, or parts thereof, in which a higher temperature than that of the atmosphere is, at any time, desired. Such furnaces are usually placed in the basement or cellar of the building they are designed to warm, and, for use in many and large parts of our country, have to be adapted for burning the soft or bituminous coal, which, in such localities, is the chief, and, except at a considerable cost, the only, article of fuel. Such coal, it is well known, while undergoing combustion, evolves large quantities of gas and carbon, which pass off unconsumed, and which, with the dust and ashes carried through the fire by the draught, are liable to be carried, through the registers, into the rooms to be warmed, unless the fire-space and pipes leading therefrom be, with respect to the hot-air chamber and registers, perfectly air-tight. Hence, in constructing such furnaces, particularly when they are designed for the consumption of bituminous coal, two serious difficulties have been encountered: first, to make the sides or walls of the fire-space of the furnace of such kind and thickness of material as will readily transmit heat to the hot-air chamber, and, at the same time, not be liable to speedy destruction or injury by the direct action of the fire itself; and, second, so to construct the fire-space and pipes, or other communications leading therefrom, that no dust, smoke, gases of combustion, or other deleterious or offensive matter, shall escape into the apartments to be warmed. My invention consists in the construction of a hot-air heating-furnace for warming buildings generally, or parts thereof, and calculated effectually to obviate these difficulties.

To enable others skilled in the art to make and use my invention, I will proceed to describe its construction and mode of operation.

a is the floor of my improved heating apparatus, resting on the cellar-bottom or other desirable foundation; *a'*, the rear and side walls; *a''*, the covering or roof, and *b* the front wall, all of brick or other desirable material, and of such thickness and so built as to be air-tight, except at the proper apertures, as hereinafter to be mentioned. Inside this I construct a fire-space, *c*, having side walls *d d*, and a rear wall, *d'*, all of fire-brick, or lined with fire-brick. By these I support the fire-grate *e* and the front end of the heater *f*. This heater *f* I make of heavy rolled or sheet metal, of cylindrical or other desirable shape, except that on the lower side, at its front end, I cut out a section, as shown in fig. 1, so that the fire-space *c* shall be uncovered, and open directly into the heater *f*. The section thus taken out leaves a notch in the heater *f*, in depth about equal to the depth of the fire-space *c*, and in height sufficient to give the fire a free and open passage upward into the heater *f*. The joints of the heater are, by riveting or otherwise, made air-tight; and, for the purpose of securing similar joints where it joins the masonry, I make flanges *i i* along the edges of the notch, cut as above set forth, which flanges are built into the masonry, substantially as shown in the drawings. The pipe *g* also makes an air-tight joint with the heater *f* and roof *a''*, through which it leads into the chimney, so that no dust, or smoke or noxious gases which come from the fire in the fire-space *c*, can escape into the apartments of the house through the air-chamber *h*. The supporter *l* sustains the rear end of the heater *f*, though other means of support may be substituted in lieu thereof. The rear wall *d'* of the fire-space *c* has a flue, *m*, leading from below the grate *e* to the fire above the grate, or into the heater *f*. It is opened and closed by a damper, *n*, to regulate the draught. It is also used as an ash-flue, and for other similar purposes, in the usual manner. The chimney *z*, or pipe *q*, has a similar damper, *z'*, also for regulating the draught. *o* is a door opening into the fire-space *c*, and *p* a door closing the man-hole, to be opened for convenience of cleaning. One or more pipes *s* lead from the air-chamber *a* to registers, or otherwise open into the various apartments to be warmed; and, if desired, one or more similar

pipes s' lead from such apartments back to the air-chamber h , to supply fresh air; or fresh air may be introduced from without in any desirable way. If it be desired to heat an apartment or building rapidly, the pipe s' may be used, whereby cold air will be conducted out of the room as fast as hot air is let into it, and such circulation be kept up till the room is properly heated, when, by properly-constructed dampers, the pipe s' may be closed; and, as heated air naturally rises, the pipe s should lead from near the top of the air-chamber h , and the pipe s' discharge near the bottom.

I prefer the drum or boiler-shaped heater f to heaters of other forms. It can be constructed at small cost, and, being made of rolled or sheet metal, is less liable to injury from the heat by alternate and irregular expansion and contraction. It presents a large amount of heating surface for receiving and transmitting heat. I make it usually, for ordinary dwelling-houses, about six feet in length, by from thirty to forty inches in diameter, more or less, varying the proportions somewhat, as may be necessary or advisable, and varying also the shape, provided an equivalent surface be secured for the radiation of heat into the air-chamber h . Then, when such heater f is placed over a fire-space c in the manner described, the requisite amount of heat can usually be obtained without raising the heater f even to a red heat; and practically I have found it difficult to reach that temperature, since it seldom, if ever, happens that either the flame or the current of hot air from the fire strikes directly against the heater f in any part. Consequently the action of the heat on its interior surface will be more uniform than in the heaters of such furnaces generally, so that liability to injury from unequal expansion and contraction will be almost entirely obviated. Also, since the heater f is air-tight with respect to the surrounding air-chamber h , no smoke, dust, unconsumed gases, or carbon, can escape into the chamber h to mix with the heated air therein; and I claim it as especially superior for this purpose. The impurities above named, resulting from the combustion of bituminous coal, are in no case allowed to mix with the air in the air-chamber h ; or, if anthracite coal be used, the carbonic acid gas evolved therefrom while burning is, with other noxious gases, carried off in like manner. I burn not only the articles of fuel in general use for the production of heat, but, in connection with suitable apparatus for burning the same, I also employ petroleum and its products and compounds.

By building the walls $d d'$ inside the outer walls $\alpha \alpha'$, so that the air of the chamber h shall receive heat from the fire-space c on three of its sides, as well as from the heater f , I add an additional improvement. The surface for radiating heat is thus brought to a maximum. The heat transmitted through these walls $d d'$, instead of passing off into the atmosphere of the cellar or basement and being wasted, is utilized and applied to heating the room or rooms to be warmed.

Another important advantage consists in the fact that the walls of the fire-space c are made entirely of brick, which is separate from, and forms no part of, the drum f , whereas, in heaters of ordinary construction, the fire-pot is attached to and forms part of the heater, so that, when the former burns out, both heater and fire-pot have to be removed for renewal or repair; but, by my improvement, the heater f is, by the flanges i , built into the walls $b d d'$, so connected therewith as not only to make tight joints, but that the lining of the brick fire-space may be easily repaired or renewed from time to time without disturbing the heater. The annoyance of the escape of smoke and dust into the air-flues is thus also effectually prevented.

What I claim as my invention, and desire to secure by Letters Patent, is—

The drum or heater of sheet or plate iron, with an opening in its bottom and front, connecting with a fire-space, c , of brick, the edges of the heater or drum around such opening having flanges i built into the furnace-walls, constructed and arranged substantially as described for the purposes specified.

In testimony whereof I, the said BIDDLE ARTHURS, have hereunto set my hand in presence of—

BIDDLE ARTHURS.
